MEAT TENDERIZER

Daniel B. Stauft, 5494 Galbraith Road,
Cincinnati, Ohio 45236

Filed Nov. 6, 1972, Ser. No. 303,860

Term of patent 14 years

Int. Cl. D7—04

U.S. Cl. D7—153

Fig. 1

Fig. 2

Fig. 3

FIG. 4

FIG. 5

FIG. 6

FIG. 1 is a perspective view of a meat tenderizer embodying my new design;

FIG. 2 is a front elevational view of the meat tenderizer;

FIG. 3 is a rear elevational view of the meat tenderizer;

FIG. 4 is a side elevational view of the meat tenderizer, the opposite side of which is a mirror image of this side;

FIG. 5 is a top plan view of the meat tenderizer; and

FIG. 6 is a bottom plan view of the meat tenderizer.

I claim:

The ornamental design for a meat tenderizer, substantially as shown and described.
